BRUSH AND BRUSH MATERIAL

Ruben O. Peterson, University Heights, Ohio, assignor to The Osborn Manufacturing Company, Cleveland, Ohio, a corporation of Ohio

Application July 14, 1947, Serial No. 760,847

12 Claims. (Cl. 51—190)

1

This invention relates, as indicated, to brushes and brush material, and more particularly to brush material designed for very hard usage.

Brushes, and especially rotary brushes, have long been employed to apply abrasive and polishing materials to clean, smooth and polish metallic surfaces and the like. Cotton buffering wheels and Tampico fibre brushes, for example, are commonly employed for this purpose but are far from being entirely satisfactory. They not only wear more rapidly in use than is desirable but also waste an unnecessarily large proportion of the abrasive material supplied to them. There is a tendency for these brushes when rotated at high speeds to overheat with resultant "burning" of the brushing material and such tendency is accentuated by the presence of abrasives between the strands. Due to uneven application of the abrasive, work is done at an uneven rate, and the excessive amount of lint cast off by the ordinary buff or string brush is a fire hazard. Other causes tending to shorten the lives of such brushes include cutting of brush fibres by abrasive and the work-piece when excessive pressure is used in an effort to compensate for ineffective application of abrasive, and the action thereon of acids or alkalis encountered under certain working conditions.

It is, therefore, a primary object of this invention to provide brushes and brushing material which will be effective to clean, scour and polish metallic surfaces and the like and which will also have a greatly increased useful life.

A further object is to provide such material and brushes comprising the same which will be resistant to the action of acids and/or alkalis.

Still another object is to provide brushing material which will carry and apply abrasive or polishing materials with a minimum of waste.

To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of various structural forms in which the principle of the invention may be used.

In said annexed drawing:

Fig. 1 is a side elevational view, partly cut away, of a rotary brush section employing brush material in accordance with my invention;

Fig. 2 is an enlarged view of one type of material treated in accordance with my invention;

2

Fig. 3 is a view of similar material illustrating one manner in which the same may be rendered acid and alkali proof;

Fig. 4 is a sectional view of the material of Fig. 2;

Fig. 5 is a sectional view taken through a rotary brush section as illustrated in Fig. 1;

Fig. 6 is a fragmentary view of a brush section illustrating an embodiment employing an alternative form of brushing material;

Fig. 7 is a view of the braided strip or tape employed as brushing material in the brush of Fig. 6;

Fig. 8 shows a sheet of plastic in which abrasive is embedded from which stranded brush material may be produced in accordance with my invention;

Fig. 9 shows a brush strand produced from the sheet of Fig. 8;

Fig. 10 is an enlarged sectional view taken on the line 10—10 on Fig. 9;

Fig. 11 shows a strip of sheet material such as paper or fabric to which abrasive particles have been adhered except for a portion of one side, and from which stranded brush material may be produced;

Fig. 12 is a fragmentary view of a composite strand of brush material comprising an inner core of fine filaments and an outer sheath; and

Fig. 13 is a side view, on a reduced scale, of the entire brush of which a portion is shown in Fig. 1.

In one embodiment of my invention I employ a braid of tightly twisted strands such as braided tire cord or "cable-cord" since the tightly twisted strands do not unravel in use with nearly the rapidity of loosely twisted strands and also, when braided and treated as explained below, are relatively stiff enabling the brush to retain its form much better than when limper sorts of cordage and the like are employed. Referring now more particularly to the drawing, a brush formed in accordance with this invention may comprise a circularized channelform brush back 1 in which brushing material 2 is held by a retaining member such as wire 3. It will, of course, be understood that the material of this invention may be employed in other than annular or helical brush backs although it is primarily in the field of rotary brushes that there is the greatest need for the novel qualities of such material. The brush back may desirably be indented as at 4 to prevent displacement and packing of the brushing material. The brush material may likewise be retained in a brush back of the type

50

described in my Patent No. 2,303,386, dated December 1, 1942. Brushes similar to those described in my prior Patents Nos. 2,409,309; 2,345,422; 2,320,384; 2,316,185, and Whittle Patent No. 2,288,337 are especially adaptable for use with the brush material herein specified.

A further advantage of the braided material resides in its tendency to form excellent abrasive carrying tufts 5 making an ideal surface to the finished brush. This is particularly striking when compared to Tampico fibre brushes now generally employed which permit powdered abrasive to filter down between the fibres in addition to dropping a good deal of it, rather than holding it in working position. It has been found possible economically to remove marks from steel surfaces by employing brushes made in accordance with my invention where such was not previously feasible.

The material of this invention may also be stiffened by impregnating with a hardening and stiffening agent such as glue 6 (see Figs. 2 and 4) which will desirably be set and toughened by subsequent treatment with an agent such as formaldehyde and, optionally, a solution of sodium silicate (waterglass). Such agent penetrates between and thoroughly wets the fibres in addition to coating the surface of the cord or like material. The resultant product is very hard and tough, relatively waterproof, and is capable of considerable abrasive action of its own. Such abrasive action may be further enhanced by applying an abrasive substance such as emery dust prior to the hardening step and preferably prior to or at the same time that the glue is applied. A superficial coating of the brushing material, as with rubber, is ineffective for this purpose, it being necessary to employ an impregnating and stiffening agent which will penetrate between and wet the fibres. For this reason it is often desirable that a wetting agent be present if an aqueous solution of glue be employed as a stiffening agent. The above treatment not only produces a hard tough brushing material but also aids in preventing unravelling of the strands. Instead of braided cord of the generally circular form illustrated in Figs. 1 to 5 inclusive, flat braided strips 7 of fabric, as shown in Fig. 7, may be treated in a similar manner and employed as shown in Fig. 6. The term "cord" as employed herein and in the claims is to be understood as including both such forms of brushing material. Other embodiments of the invention are obvious to those skilled in the art. When the fabric is to be impregnated with the stiffening agent, it is generally not necessary to employ hard braided material and a relatively soft braid is entirely satisfactory and sometimes preferable.

The material of this invention may be further treated, if desired, to render the same water, acid and alkali proof. This may be done by coating the cord or other material with a thin film of certain synthetic plastics, such as "Pliofilm." One method of thus coating braided tire cord, for example, is illustrated in Fig. 3 where a narrow strip 8 of "Pliofilm" is wrapped in slightly overlapping spirals about the cord. Heat and pressure are then applied to weld the strip into a continuous impervious coating. Obviously, this treatment may be applied to the hard-braided cord or the soft-braided but impregnated cord, etc., as desired.

In each of the above-described forms of my improved stranded brush material it will be noted

that the individual strands comprise smaller strands or fibers assembled in general criss-cross relation, specifically to form a braided cord in counterdistinction to twisted and other types of cord in which the fibers are arranged in general parallel relation. As is well known, the latter types of cord are structurally the stronger since the slippage between the individual fibers permits an adjustment to allow the aggregate strength of the fibers to resist a given stress. However, what has not been heretofore recognized in attempting to use such cord as brush material where the component strands are subjected to severe flexing as well as terminal and side wearing action when in use, is that when the cord is treated with a material of low limit of resilience such as a plasticized glue compound, this adjustability is reduced or eliminated. In other words, the impregnated and stiffened cord is only as strong as the impregnating material plus the strength of the few fibers that happen to be in a position to function when a stress is applied. The foregoing explanation, it is believed, accounts for the fact that cords treated in the manner described are weaker than the untreated cord, unless the latter be held under tension while being treated. It is for this reason that for some uses it has been found desirable to hold the cord under tension while being treated with a binding material so as to add the strength of the latter to that of the aggregate strength of the fibers (Cf. Pat. No. 2,220,958 to Jennings).

In counterdistinction to the foregoing, the present invention is based on the discovery that increased tensile strength is not the only requisite in brush material made from cord, but that it is very important that such material be capable of withstanding the wear, and particularly the beating and flexing, that it will encounter when made into a brush. Actually such cord will stand up better if the outer fibers composing the same are not under tension but somewhat loosely looped so that flexing will not over-strain them. For this reason, a braided cord, for example, while not a good construction for attaining maximum tensile strength, has been found highly satisfactory for the purpose in hand, in that it has an open structure, is very well suited to withstand flexing after the described treatment and has greater non-ravelling characteristics than a twisted cord. Furthermore, since the component strands or fibers of such braided cord lie at angles to each other, i. e. in general criss-cross relation, rather than in general parallel relation, the cord is provided with uniformly distributed pocket-like interstices which receive and retain an adequate amount of the treating material. Moreover, where the latter contains a finely ground abrasive, the latter will be retained in such interstices despite absorption by the fibers of the cord of a portion of the treating agent which serves as the vehicle for introducing such abrasive.

The ideal abrasive-carrying brushing material requires to have several rather conflicting characteristics which have in the past prevented any really satisfactory solution. The abrasive should be incorporated into the brush material instead of being fed thereto since such latter method is messy and wasteful, and does not provide a uniform concentration of abrasive at the work-piece. Loose abrasive particles between the strands of the brush material and abrasive which is superficially exposed on the lateral surfaces cause the generation of excessive heat and cutting of such

strands. On the other hand, if the abrasive particles are to have an efficient cutting action they should not ordinarily be entirely embedded or submerged in a solid supporting medium or matrix.

I have successfully solved this problem, as shown by actual tests, by providing stranded brushing material having a relatively smooth exterior surface but with abrasive contained internally thereof. As the ends of the strands wear down additional abrasive is exposed in position to contact the work but there is little friction between the strands themselves as they are flexed, greatly reducing heat generation and resulting tendency to burn. It will be seen, therefore, that I have produced stranded brush material which has increased abrasive action at its ends but minimized abrasive action along its length.

Referring now more particularly to Figs. 8-11 inclusive, such figures illustrate one embodiment of my invention whereby such results may be achieved. A thin film or strip 9 of a plastic such as Pliofilm (rubber hydrochloride-rubber derivatives and rubber-like resins) or nylon (a polyamide resin) serves as the base in which particles of abrasive 10 may be embedded as by rolling. Or such particles may be cemented in place either by means of an adhesive or by use of a little solvent effective to render the surface of the sheet gummy and which then evaporates. In whatever manner the abrasive particles are embedded or adhered they will in effect be mounted on the surface where they are enabled to exert full cutting action. The strip 9 will then be rolled or twisted as shown in Fig. 9 to form a strand useful as brush material. Obviously this may be carried out as a continuous process employing a long strip of plastic, and the resultant strand cut into desired lengths.

As shown in Fig. 10, the particles of abrasive 10 project into the interstices between the convolutions of the twisted strip where they will be exposed at the ends of the strands for effective cutting action. The overlapping seams 11 may be heat-treated to weld the same or cemented by treatment with solvent or adhesive, thereby providing a smooth exterior surface affording a minimum of frictional resistance to relative movement of the strands in the rapidly rotating brush.

As shown in Fig. 11, the plastic strip 9, instead of having abrasive particles secured to one side only, may have such particles on both sides except, preferably, for an area 12 which will form the exterior surface of the strand when the strip is rolled as above. In this way it is possible to greatly increase the abrasive content of the finished strand.

Instead of using a strip of plastic, paper, preferably of "super-kraft" strength, may be employed, the abrasive particles being cemented thereto and the strand formed by twisting or rolling. Such strand may be treated to secure the same in twisted condition as by means of adhesive or a wax coating. Various fabrics such as cotton cloth may be similarly employed. Care should be taken that adhesives and the like are of a type which will have little or no tendency to smudge the surface of the work-piece to be brushed, and such smudge as may be produced should be easily removable by ordinary cleaning methods.

It has been found that for many purposes relatively fine filaments or fibers provide a much more satisfactory brushing action than fibers of

larger diameter. In particular, brush material made up of small filaments of a diameter less than ten one-thousandths of an inch (cotton fibers are about four ten-thousandths) will give a fine surface on metal parts for plating, for example. Unfortunately, the smaller the composite strands of the brush material the greater is the tendency to generate frictional heat. I therefore assemble a body of such small filaments as a core and encase the same in a sheath which has the advantages above described and additionally substantially reduces relative movement of the individual filaments. A sliver of such fine filaments 13 may be passed through a bath or slurry containing adhesive and abrasive material 14 and then twisted, dried and encased in a sheath 15 of plastic, paper or fabric (see Fig. 12). Such sheath may be adhered to the adhesive impregnating the twisted strand if such adhesive has not been entirely dried, or otherwise treated to keep it in position. The tuft 16 of fine filaments formed at the end of the strand provides an excellent polishing and finishing face to the brush. I have found that the heat generated by the interaction of the brushing material may thus be greatly reduced, and in one case found a reduction to about one-eighteenth that developed when the composite filaments were about one two hundredths the diameter of my new material.

Fibrous material such as American hemp, for example, may be passed through a slurry of abrasive while in sliver form and then twisted into abrasive-containing strands. Such strands will then be given an outer coating, as of liquid nylon or wax, and are ready to be incorporated into a rotary brush. This surface coating in effect encases the composite strand and minimizes abrasive cutting action between the strands themselves. Chlor-naphthalene is an example of a wax-like coating material which is suitable for thus coating the strands of brushes designed for certain uses.

A great advantage of this type of strand is that short (and therefore cheap) fibers may be employed which are not otherwise useful since twisting of the filaments together provides a strand of indefinite length and the sheath of plastic or other coating confines the fibers and prevents loosening thereof with resultant disintegration of the strand. The bonding agent such as glue also assists in securing the fibers together.

In the past, buffing operations have been performed almost entirely by means of buffs composed of woven fabric. Such buffs, however, suffer from several serious disadvantages. Since more than one-half of the threads or fibers of the fabric are non-radially disposed such threads are easily shed and the buff disintegrates and becomes irregular much more rapidly than it actually wears away. The layers of fabric afford a solid face which will not conform to a slightly uneven surface on the workpiece as do the strands of a true brush. It will be seen that my new brushing material will surpass the usual cloth buff in abrasive-holding ability, in the action of the ends of the brushing strands in conforming to the surface of the work-piece, and in providing firmly held fine filaments an abrasive at the brush face where it is needed.

Attempts have been made to use as brush material flat strips of emery cloth held with the flat surfaces in the plane of the shaft when extended as during rotation of a brush, but without much success for obvious reasons. The exposed

abrasive tends to cause development of excessive heat and promotes self-destruction of the material. I overcome these problems by forming the strips into strands with at least the major portion of the abrasive internally thereof. Such strands afford greater density of brush material at the brush face and avoid the difficulty of shedding threads which otherwise is so prevalent.

It will be seen that I have provided a new type of brush material and a new brush capable of greatly improved brushing action and a longer and more economical life. Such brushes may be rotated at much greater speeds than ever before without danger of "burning" and with a much increased production of finished work-pieces. At the same time, such material and brushes may themselves be produced in large quantities and at little expense.

This application is a continuation-in-part of my co-pending application Serial No. 427,466, filed January 20, 1942, now abandoned in favor of this application.

Other modes of applying the principle of the invention may be employed, change being made as regards the details described, provided the features stated in any of the following claims or the equivalent of such be employed.

I therefore particularly point out and distinctly claim as my own invention:

1. As a new article of manufacture, brushing material of the character described comprising a flexible strand formed of twisted fabric sheet material having abrasive particles adhered thereto, said fabric sheet material being twisted to bring such adhered abrasive particles substantially entirely internally of said strand, and projecting into the interstitial openings thereof.

2. As a new article of manufacture, brushing material of the character described comprising a flexible strand formed of twisted paper having abrasive particles adhered thereto, said paper being twisted to bring such adhered abrasive particles substantially entirely internally of said strand and projecting into the interstitial openings thereof.

3. As a new article of manufacture, brushing material of the character described comprising a strand formed of twisted plastic sheet material having abrasive particles embedded therein, said sheet being twisted to bring such abrasive particles internally of said strand and projecting into the interstitial openings thereof and leaving a non-abrasive carrying surface of said sheet material exposed.

4. As a new article of manufacture, brushing material of the character described comprising a flexible strand formed of twisted sheet material having abrasive particles secured thereto, said sheet being twisted to bring such abrasive particles internally of said strand and to leave a non-abrasive-carrying surface of said sheet material exposed.

5. As a new article of manufacture, a rotary brush having a back and flexible stranded brushing material extending therefrom, such brushing material comprising strands formed of twisted web material having abrasive particles adhered thereto, said web material being twisted to bring such adhered abrasive particles substantially entirely internally of said strand and projecting into the interstitial openings thereof with a substantially non-abrasive-carrying surface of said web material left exposed.

6. As a new article of manufacture, a rotary brush having a back and flexible stranded brush-

ing material extending therefrom, such brushing material comprising strands formed of paper having abrasive particles adhered thereto, said paper being deformed to bring such adhered abrasive particles substantially entirely internally of said strand and projecting into the interstitial openings thereof with a substantially non-abrasive-carrying surface of said paper left exposed.

7. As a new article of manufacture, a rotary brush having a back and stranded brushing material extending therefrom, such brushing material comprising individual flexible strands formed of plastic sheet material having abrasive particles embedded therein, said sheet being deformed to bring such abrasive particles internally of said strand and projecting into the interstitial openings thereof, said strand being secured in such deformed condition with a non-abrasive surface of said sheet material exposed to form the exterior of said strand.

8. As a new article of manufacture, a rotary brush having a back and flexible stranded brushing material extending therefrom, such brushing material comprising strands formed of sheet material having abrasive particles secured thereto, said sheet being deformed to bring such abrasive particles internally of said strand, with a substantially non-abrasive carrying surface of said sheet left exposed.

9. As a new article of manufacture, a rotary brush having stranded brushing material comprising strands formed of twisted sheet material, treated with a bonding agent effective to maintain such strand in twisted condition.

10. As a new article of manufacture, a rotary brush having stranded brushing material comprising strands formed of twisted sheet material, and abrasive adhered thereto, the major proportion of such abrasive being internally of said twisted strand.

11. As a new article of manufacture, brushing material of the character described comprising a strand formed of twisted plastic sheet material having abrasive particles embedded therein, said sheet being twisted to bring such abrasive particles internally of said strand and projecting into the interstitial openings thereof, and said plastic being heat-sealed to secure the same in such twisted condition, with a non-abrasive surface of said sheet material exposed to form the exterior of said strand.

12. As a new article of manufacture, brushing material of the character described comprising a strand formed of twisted plastic sheet material having abrasive particles embedded therein, said sheet being twisted to bring such abrasive particles internally of said strand and projecting into the interstitial openings thereof, and said plastic being cemented in such twisted condition, with a non-abrasive surface of said sheet material exposed to form the exterior of said strand.
